CLAIM

The ornamental design for a solar-powered cattail light, as shown and described.

DESCRIPTION

FIG. 1 is a perspective view of a solar-powered cattail light in accordance with the present invention;

FIG. 2 is a first side view of the solar-powered cattail light shown in FIG. 1;

FIG. 3 is a second side view of the solar-powered cattail light shown in FIG. 1;

FIG. 4 is a third side view of the solar-powered cattail light shown in FIG. 1;

FIG. 5 is a fourth side view of the solar-powered cattail light shown in FIG. 1;

FIG. 6 is a top view of the solar-powered cattail light shown in FIG. 1; and,

FIG. 7 is a bottom view of the solar-powered cattail light shown in FIG. 1.

The broken lines are for illustrative purposes only and form no part of the claimed design.
